(57) **CLAIM**

The ornamental design for a faceplate for a server, as shown and described.

DESCRIPTION

FIG. 1 is a top, front and side perspective view of a first embodiment of a faceplate for a server embodying the new design which shows the faceplate attached to a server.

FIG. 2 is a top view thereof.

FIG. 3 is a bottom view thereof.

FIG. 4 is a first side view thereof.

FIG. 5 is a second side view thereof.

FIG. 6 is a front view thereof.

FIG. 7 is a back view thereof.

FIG. 8 is a top, front and side perspective view of the first embodiment of the faceplate for a server which shows the faceplate detached from a server.

FIG. 9 is a top view thereof.

FIG. 10 is a bottom view thereof.

FIG. 11 is a front view thereof.

FIG. 12 is a back view thereof.

FIG. 13 is a first side view thereof.

FIG. 14 is a second side view thereof.

FIG. 15 is a top, front and side perspective view of a second embodiment of a faceplate for a server embodying the new design.

FIG. 16 is a top view thereof.

FIG. 17 is a bottom view thereof.

FIG. 18 is a front view thereof.

FIG. 19 is a back view thereof.

FIG. 20 is a first side view thereof; and,

FIG. 21 is a second side view thereof.

Broken lines are used to illustrate features of the faceplate for a server which form no part of the claimed design. In FIGS. 1-7 a server is shown to represent the environment of the faceplate for a server which forms no part of the claimed design. The dot-dash line of FIGS. 15-21 illustrates an unclaimed boundary.
